UNITED STATES PATENT OFFICE.

JOHN EDWARD BURNS, OF FLUSHING, NEW YORK.

CASTING-MACHINE.

1,373,794.

Specification of Letters Patent.

Patented Apr. 5, 1921.

Application filed July 2, 1919. Serial No. 308,285.

To all whom it may concern:

Be it known that I, JOHN EDWARD BURNS, a citizen of the United States, and a resident of Flushing, county of Queens, and State of New York, have invented certain new and useful Improvements in Casting-Machines, of which the following is a specification, reference being had to the accompanying drawing.

10 My invention relates to new and useful improvements in casting machines and more especially to such as are used for dental work, and its object is to provide a simple and efficient apparatus for forming castings under pressure. More specifically its object is to provide an easily controlled device for sealing the molding flask and then admitting air under pressure thereto.

20 A still further object is to provide an automatic arrangement for drawing air from the bottom of the flask, when air under pressure is admitted to the upper part thereof.

25 These and other objects of the invention will appear in the following specification in which I will describe the invention, and the novel features will be set forth in the appended claims.

Referring to the drawings:

30 Figure 1 is a sectional side elevation of the device, which is made according to and embodying this invention with the parts thereof shown in two of their different relative positions.

35 Fig. 2 is a similar view of some of the parts shown in Fig. 1 with the parts shown in a third operative position.

Fig. 3 is a sectional view of another form of one of the interchangeable plunger caps.

40 Like characters of reference designate corresponding parts in all of the figures of the drawings. 10 designates a base on which the various parts of the apparatus are mounted. 11 is a frame or bracket affixed 45 to this base and forming a table 12 and two spaced plunger bearing supports 13 and 14. Above the table a link 15 is pivoted to the frame at 16 and to an actuating lever 17 at 18.

50 20 is a hollow rod which slides vertically in the supports 13 and 14. A collar 21 is fixed to this rod to which collar the lever 17 is pivotally connected at 19. Another collar 22 is slidably supported on the lower 55 end of rod 20 to which is fixed a plunger head 23. This is internally threaded to re-

ceive any one of a number of different plunger caps, such as that shown at 24 in Figs. 1 and 2 or that shown at 24^a in Fig. 3. 25 is a valve rod fixed to the collar 22 and extending up through the hollow rod 20 at which upper end is a valve 26.

30 is a valve casing which forms a valve seat 31, which, with the valve 26 divides the valve casing into two chambers 32 and 33 65. This valve casing also has a recess 34 which acts as a guide at the upper end of the valve rod 25.

A tank 40 is divided by a partition 41 into a pressure chamber 42 and a vacuum 70 chamber 43. 44 is a pump connected with these two chambers through check valves 45 and 46, respectively, which are faced opposite so that when the plunger of the pump is actuated air will be withdrawn from the 75 chamber 43 and forced into the chamber 42. 47 is a pressure gage on the tank 40. A pipe 48 leads from the pressure tank to an adjustable regulating valve 49, which is mounted on the bracket 11. A flexible tube 80 35 leads from the pressure regulating valve to the chamber 32 of valve casing 30. Another flexible pipe 36 leads from the chamber 33 to the inside of the plunger head 23 with which it is connected as at 37 at an 85 angle inclined to the vertical.

On the table 12 is a block 50 which is connected with the vacuum chamber of the tank 40 by a pipe 51. The end of an exhaust port 52 with which this pipe is connected is controlled by a slide plunger 53 in which is a port 54. A perforated transverse wall 55 within this plunger is engaged by a compression spring 56, the other end of which is in engagement with a lower cap 57 95 screwed into the bottom of the block 50. The plunger 53 is provided at its lower end with an extending flange 58, which by engaging a shoulder formed in block 50 limits the upper movement of the plunger 53 and 100 holds it in the position in which it is shown in Fig. 1 with its port 54 above and out of alignment with the end of the exhaust port 52.

60 and 61 are two parts of a molding flask 105 in which is suitable investment material 63, except for the mold cavity 64 which has been left by a pattern of the article which is to be cast. This flask is supported in a cup like member 65, the lower end of which 110 forms a hollow boss 66 into which some of the investment material 63 extends, which

boss is screwed into the upper end of plunger 53. 67 is a cap for the top of the member 65, the upper part of which forms a hollow boss 68, through which the molten metal 5 may be introduced into the chamber 64 through the sprue-hole leading upwardly therefrom. At the bottom of the plunger cap 24 is a gasket 69, which is adapted to be pressed over and to seal the joint between 10 the cup like member 65 and its cover 67.

70 is a perforated thimble on the upper end of which is a flange 71 by means of which the thimble is held between the plunger head 23 and the plunger cap 24.

15 The operation of this device is as follows: The molding flask is prepared in the usual manner to receive molten metal, after which it is placed in the position in which it is shown in Figs. 1 and 2, while the plunger 20 cap 24 is raised to the position in which it is shown in dotted lines by 24^b in Fig. 1. The molten metal is poured into the flask in the usual way.

Now the piston of pump 44 is actuated until the desired amount of pressure is formed 25 in the chamber 42 and at the same time a partial vacuum will be formed in the chamber 43. The regulating valve 49 is now adjusted to permit air at the desired amount of 30 pressure to be admitted through tube 35 into the chamber 32 of the valve member 30. Now the lever 17 is moved downwardly to bring the plunger cap 24 into engagement 35 with the mold flask and its supporting parts and the various parts of the apparatus will then assume the relative positions in which they are shown in Fig. 1. Further downward movement of the actuating lever 17 will cause a relative movement of the hollow 40 rod 20 and the valve rod 25, which will result in raising the valve 26 from its seat 31. Air under pressure will then be transmitted through tube 36 into the plunger head 23 at an angle so that it will not be directly blown 45 through the hollow boss 68 into the sprue-hole. In order to further diffuse the air blast the thimble 70 is provided. This diffusion is important because of the fact that a direct current of air into the mold cavity 50 would result in disturbing the molten metal therein. This air under pressure results in forcing the molten metal into the mold cavity 64 so that a perfect and dense casting results. It also has a certain cooling effect 55 upon the metal which accelerates the operation.

When the actuating lever 17 is depressed to its fullest extent it will result in pressing the spring 56 and allowing the plunger 53 60 to move down into the position in which it is shown in Fig. 2 with its port 54 in alignment with its exhaust port 52. This will cause air to be sucked out from the bottom of the flask through the investment material 65 so that if any air pockets have been

formed in the mold cavity 64 they will be removed and a more perfect casting formed.

The plunger cap 24^a of Fig. 3 is added for the purpose of showing that plunger caps of different sizes and shapes may be 70 interchangeably used with this apparatus. It is obvious, of course, that the mold flasks themselves vary in size and shape with the kind of work which it is to be done with them. The apparatus, of course, is not limited in any way to the particular form of molding flask herein shown and described nor to the specific use, which has been described, of the apparatus for dental work. 75

The invention upon which this application is based is broader than the apparatus which has been shown and described for the purpose of illustrating one of the possible embodiments thereof and I do not intend any limitations other than those imposed 80 by the appended claims.

What I claim is:

1. In a casting machine, the combination of a molding flask open at opposite ends, a source of compressed air, a hollow plunger 90 cap adapted to seal the top of the flask, an inlet valve for admitting air to the plunger cap, means for withdrawing air from the bottom of the flask, an outlet valve for controlling said air withdrawing means, and 95 movable means for first bringing the said flask and cap together, said means being arranged to have a further movement in the same direction imparted to it for actuating the inlet valve, and a still further movement 100 for actuating the outlet valve.

2. In a casting machine the combination of a flask open at opposite ends, a hollow support therefor, means for withdrawing air from the bottom of the flask, an outlet 105 valve for controlling said air withdrawing means, and means for depressing the flask support and thereby actuating said outlet valve.

3. In a molding machine, the combination 110 of a flask open at opposite ends, a hollow vertically movable support therefor, a spring for forcing said support upwardly, means for withdrawing air from the bottom of the flask, an outlet valve for controlling 115 said air withdrawing means, the support forming a part of said valve, and means for depressing the support against its spring to open the outlet valve.

4. In a casting machine, the combination 120 of a molding flask open at opposite ends, a hollow support therefor, a source of compressed air, a hollow plunger cap adapted to seal the top of the flask, an inlet valve for admitting air to the plunger cap, means for 125 withdrawing air from the bottom of the flask, an outlet valve for controlling said air withdrawing means, and means for bringing said flask and cap together, depressing the flask support and thereby actuating the inlet 130

valve and for depressing the flask support and thereby actuating said outlet valve.

5. In a casting machine, the combination of a molding flask open at opposite ends, a hollow vertically movable support therefor, a spring for forcing said support upwardly, a hollow plunger cap adapted to seal the top of the flask, an inlet valve for admitting air to the plunger cap, means for withdrawing air from the bottom of the flask, an outlet valve for controlling said air withdrawing means, the support forming a part of

said valve, movable means for first bringing the said flask and cap together, said means being arranged to have a further movement 15 imparted to it in the same direction for actuating the inlet valve, and a still further movement in the same direction for depressing the support against its spring to open the outlet valve.

10 In witness whereof, I have hereunto set my hand this 22nd day of June, 1919.

JOHN EDWARD BURNS.
